Filed Dec. 15, 1966, Ser. No. 5,052

Term of patent 14 years

(Cl. D54—1)

FIGURE 1 is a side elevational view of a combined support and holder for trash receptacles showing our new design;

FIGURE 2 is an enlarged top plan view of a double arcuate receptacle supporting bracket comprising a part of the design;

FIGURE 3 is a bottom plan view thereof;

FIGURE 4 is a side elevational view thereof;

FIGURE 5 is an end elevational view thereof;

FIGURE 6 is a side elevational view of a double hook element comprising a part of the design;

FIGURE 7 is a top plan view thereof;

FIGURE 8 is a bottom plan view thereof; and

FIGURE 9 is an end elevational view thereof.

The design is characterized by the parallel arms extending from a central ring and directly connected with arcuate channels on the ends thereof, all as shown.

The broken line showing of two trash receptacles in FIG. 1 is for illustrative purposes only.

We claim:

The ornamental design for a combined support and holder for trash receptacles, substantially as shown and described.
